UNITED STATES PATENT OFFICE

JOSEPH D. BELL, OF SAN FRANCISCO, CALIFORNIA

DAVENPORT

Continuation of application Serial No. 706,066, filed April 12, 1924. This application filed May 14, 1928.
Serial No. 277,490.

This application is a continuation of my application for davenports Serial No. 706,066, filed April 12, 1924.

This invention has to do with the provision 5 of a simply constructed, comparatively inexpensive, strong and substantial sofa bed or davenport which may be made up in the popular style known as a Chesterfield, and to embody a full sized double folding bed of sturdy 10 construction, which bed may be operated with comparative ease and facility in being extended for use, or folded, with the full bedding equipment thereon, into a concealed position behind the seat and back members.

15 The construction of the invention permits of the desirable and effective use of a one piece foot member or bed end instead of the separate leg and foot-board arrangement as usually employed in the ordinary sofa bed, 20 which foot member provides for a more substantial, stronger and better appearing bed construction, and also serves as a handle portion and facilitates the operation of extending and collapsing the bed.

25 The construction of the folding bed is such that the full sized bed end member may be adjustably connected with the bed and will, when the bed is folded, take up little or no room without in any manner rendering the 30 operation of folding or collapsing the bed more difficult, said foot piece being connected by links with the outer section of the folding bed and presented in upright position on the outer face of said section when the bed is 35 folded. The presentation of the foot piece in this position, when the bed is folded, provides for a ready grasping of the foot piece when it is desired to extend the bed and the force exerted thereon is transmitted to the 40 bed in such manner that the latter may be unfolded and extended with less effort on the part of the operator and more smoothly than when the bed is otherwise operated. The fact that the entire bed end member is dis-

45 posed on the outer face of the outer bed section when the bed is folded and that said bed end does not extend appreciably beyond the extremities of said bed section, permits of a compact folding of the bed as an entirety. 50 The one piece bed end of the ordinary bed

type connected with the outer section of a sectional folding bed as embodied in this invention, serves a double purpose in that beyond its function as a support for the end of the bed, it cooperates with the bed structure 55 itself, in the operation of folding and extending such structure. Thus the sectional bed and end piece are dependent upon one another and one improved by the other in the combination thereof as provided by this invention. 60

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to 70 without departing from the spirit or sacrificing any of the advantages of the invention.

Referring to the drawings:

Fig. 1 represents a cross sectional view of a sofa bed constructed in accordance with my 75 invention shown as when the bed is folded and concealed, the structure being ready for use as a sofa or Chesterfield.

Fig. 2 is a similar sectional view showing in full lines the bed as when partly extended, 80 and in dotted lines as when in the next position preliminary to full extension thereof.

Fig. 3 is a side elevation of the bed frame as when fully extended for use as a bed, certain parts being removed, the sofa frame, 85 back and seat being shown in section.

Fig. 4 is a perspective view of the bed as when extended.

Fig. 5 is a side elevation of a modified form of the invention, parts being shown in 90 cross section.

The sofa bed of this invention embodies the usual davenport or sofa frame 1, to which is connected a sectional, folding mattress or bed frame 2, which latter consists of an outer section 3, an inner section 4 and an intermediate section 5, pivoted to the other sections. The section 4 is connected between its ends with the davenport or sofa frame 1 by links 95 6 and at its rear end is vertically slidably and 100

pivotedly connected by suitable means of connection generally designated 7 with the rear part of the davenport frame. The connections between the sectional bed frame and davenport frame are such that the bed frame 5 may be extended into position of use as shown in Fig. 3, and also folded into concealed position as shown in Fig. 1, said frame when in the latter position having the front and rear 10 sections 3 and 4 disposed in upright position, slightly rearwardly inclined, with the intermediate section disposed in substantially horizontal position. This folding is such that adequate space is provided for the bedding A. 15 In association with the davenport frame is an invertible seat 8, which is connected by suitable hinges 9 with the front board 10 of said frame 1. A bar 11 is rotatably mounted in bearings 12 on the under side of the seat 20 member and has substantially right angularly disposed end portions 13 serving as links. The free ends of the portions 13 are pivoted to the intermediate bed section, or to the pivot connection of said section, with the 25 front section and as shown constituting the pivot members. The bar 11 serves as a spacing and bracing element, or in other words, as a yoke as well as a means of connection between the seat and bed frame. When the 30 seat is swung upward and outward on its hinges, the portions 13 serve as links and pull on the bed frame so as to lift the bed frame upward and outward and dispose the bed end member in position to be grasped in order to 35 complete the extension movement of the bed frame. The seat then supported by the portions 13, is lowered into position shown in Figs. 2 and 3, with the legs 15 therefor resting on the floor. The outward swinging or 40 overturning of the seat 8 swings the entire folded bed frame 2 around the rear end of the section 4 as a fulcrum. The bed frame is thus bodily lifted out of the sofa frame 1. The short section 5 in this position, is above 45 the inverted seat 8. In order to limit the swinging of the seat 8 and of the bed frame 2, relative to each other, I provide stops 16 adjacent the hinged edge of the seat 8, which stops 16 extend upwardly, when the seat is 50 overturned, so that when the bed frame 2 is lifted out of the sofa frame 1, then the bed section 5 rests upon the stops 16 thereby preventing the unbalanced weight of the bed frame to swing the seat 8 rearwardly around 55 its hinges.

A back member 17 having ears 18 is joined to brackets 19 on the davenport frame 1 by links 20, and is adapted to be swung from a position of use as shown in Fig. 1 into an 60 out of the way position inclined downwardly and rearwardly on the upper rear side of the frame 1. By means of retractile springs 21 which are joined at their ends to the brackets 19 on the frame 1 and to the back member, 65 said back member when moved past center is

maintained in its out of the way position so as to be safeguarded against falling back into position of use and possibly injuring an occupant of the bed.

In carrying out my invention instead of using the usual separate leg and foot board arrangement at the outer end of the bed frame, I provide a one piece bed end generally designated 22, which end is constructed similarly to the type of end used in the ordinary bed construction. This bed end is connected by links 23 and 24 to side members of the front bed section 3. The links 23 extend from a point above the plane of the bed frame when the latter is extended downwardly and rearwardly to their point of connection with said frame, whereas the links 24 are longer than the links 23 and extend from a point below the bed frame when extended upwardly and inwardly to a point rearward of the corresponding ends of the links 23. Thus, the solid one piece end piece when in upright position, as when the bed is extended as shown in Figs. 1, 3 and 4, extends above and below the bed and serves as a firm and substantial support for the outer end of the bed. When the bed is folded the end piece is adapted to swing so as to engage upon the then outer face of the section 2 of the bed and to be substantially within the confines of said section. When the bed is folded as shown in Fig. 1, the inner and outer sections of the bed lie in upright position with the bed end lying close against the outer face of the outer section 3 and in a position such that it will not in any way interfere with the operation of the bed nor take up an appreciable amount of room. The outer section and bed end lie in a rearwardly inclined position, and to open the bed the back member is raised and moved into position shown in Fig. 2, being held in such position by the action of the springs 21. The bed end is then accessible and presented so that it may be readily grasped and pulled outwardly. In pulling out on this bed end, the end swings on the links and the sectional bed is unfolded and extended. As the bed unfolds and extends, the operator retaining his grasp on the bed end is permitted to pull out until the bed is extended and at this time the frame assumes an upright position for supporting the bed, as shown in Fig. 3. The pull communicated on the bed frame through the bed end is such that as above stated, the operator need but pull directly outwardly in a comparatively straight line in order to unfold and extend the bed, thus the operation of extending the bed is made easier and more simple and requires less effort on the part of the operator due to the use of the bed end as a handle or lever portion while extending the bed.

As a means for insuring the proper folding of the bed into small compass, I provide inclined guides 26 on opposite sides of the

sofa frame, adapted to be engaged by projections 27 extending outwardly from the sides of the bed frame where the intermediate and front bed sections are joined and which, as shown, are the hinge members joining sections 2 and 3. When the bed is partially folded, the projections engage on the rear face of the guides and travel downwardly and rearwardly so as to cause the sections to assume the collapsed folded position shown in Fig. 1, and to be disposed as far rearwardly as possible in order that the back and seat member may be properly nested in place. The tendency of the link portions 13 in the folding of the bed is one that would cause the partially collapsed sections to be moved forwardly and downwardly, but the guide and projection arrangement overcomes this tendency and forces the said bed frame sections rearwardly.

The method of connecting the seat with the bed frame is advantageous in that it provides for a low mounting of the seat, a desirable feature in Chesterfield construction. In other words, this arrangement provides for a rearward disposition of the bed when folded, such that the seat may be made as low as desired. The position of the seat may be varied dependent upon the point of mounting the bar 11 with its portions 13 on said seat. The leverage may be increased or decreased by changing this mounting. It will be noted that when the bed is collapsed, the portions 13 swing rearwardly from their mountings on the seat and when the bed is extended, said portions swing forwardly; in the first case providing for a rearward disposition of the bed frame; and in the latter case, for the forward projection of the frame when extended, it being noted that said portions 12 are disposed in the same positions or inclination, when the seat is in its operative or inoperative position. The seat when being swung into its operative position bears upon the front face of the front bed section or the bed end which lies along said front face, and forces the said bed frame to swing downward and rearward, assisted by the projections 27 engaging on the guides 26, thus acting as a wedging or actuating element in the folding operation.

In Fig. 5, I have shown a modified form of construction of the invention wherein the bed frame consisting of outer, intermediate and rear sections 28, 29 and 30 respectively, is mounted in a sofa frame 31, in the same manner as the bed of the previously described form of the invention. The seat member 3 and other elements, not shown, are constructed and arranged in the identical manner as the previously described form of bed with the exception that the link portions 33 of the bar 34, corresponding to bar 11, which is rotatably mounted on the under side of the seat 32, are connected with the inter-

mediate section at a point forwardly of the pivot connection of said section, with the front section. This provides for disposal of the point of mounting of the links 33 on the seat at a point closer to the hinge 35 and increases the leverage action, making an easier action of extending the bed when the seat is swung on its hinge. By changing the position of the link portions 33, the thrust of said portions on the swinging of the seat into operative position is such as to cause the bed frame to swing well rearwardly as well as downwardly, without necessitating the employment of the projections and guides as utilized in the form of the invention previously described.

Having thus described this invention, what I claim and desire to secure by Letters Patent is:

1. A sofa bed comprising a sofa frame, having a back and seat hinged to the front of the frame and movable on its hinge to an inverted position in front of the frame, a bed bottom including pivotally connected sections, the rear section occupying an upright position at the back of the frame, an intermediate section occupying a substantially horizontal position at the lower end of rear section, and a front section occupying a rearwardly inclined position diagonally from the front end of the intermediate section substantially toward the top of the rear section to form a pocket when the bed is folded, the rear and the front sections being about the same length, the intermediate section being shorter than the said first sections; the rear end of said seat pressing the inclined front rearwardly when the bed is folded; connections between the rear section and the sofa frame to hold and guide the said rear section as the bed sections are extended and folded; and pivotal connections connecting the bottom of the seat to the pivotal joints of the front sections with the said intermediate sections to swing the folded bed frame around the rear end of the rear section as the seat is inverted.

2. A sofa bed comprising a sofa frame; a front board therefor; a foldable bed frame having two long end sections and a short middle section connecting the long end sections; connections between the bed frames and sofa frame to permit the bed frame to be extended or folded within the sofa frame; an invertible seat member hinged to the front board; links connecting the bed frame and seat frame adapted to lift and move outwardly the entire bed frame when the seat is lifted and to support the bed frame at a mid section when the bed is extended, both of the end sections of the bed frame extending upwardly above the seat when the bed frame is folded with the mid section in a substantially horizontal position.

3. A sofa bed comprising a housing; an in-

vertible seat mounted on one side of the housing; a foldable bed frame having two substantially equal end sections and a shorter mid section pivotally connecting them, adapted to be extended as a bed or folded within the housing; means pivotally connected to the underside of the seat and to the joints of the outer end sections with the short sections to lift the entire bed frame when the seat is lifted and to support the bed frame when it is extended, the end sections of the bed frame lying closely adjacent each other with the mid section substantially horizontal when the bed is folded.

4. A sofa bed comprising a housing; a folding bed frame having two longer sections pivotally connected to a shorter mid section and capable of forming a bed or being folded into the housing; an overturning seat hinged to the housing; a yoke carried thereby pivotally connected to the bed sections at the junction between the outer and intermediate sections for supporting the bed bottom when folded and when extended, the intermediate section lying horizontal when the bed is folded with the longer sections extending upwardly therefrom above the seat when folded.

5. A sofa bed comprising a housing; a pivotal back; a folding bed frame comprising two end sections of substantially the same length; and a shorter mid section pivotally connecting the said frame being adapted to be extended as a bed or folded within the housing; an invertible seat pivoted to the housing; links connecting said seat to the pivot points between the outer end sections and mid section adapted to raise the entire bed frame when the seat is raised; and to support the bed frame when the seat is overturned; floor supports carried by said seat arranged to lie in an upwardly inclined position under the back when the bed is folded, and to bear against the bed frame.

6. A sofa bed comprising a housing; a folding bed frame having two longer sections and a shorter mid section pivotally connecting them whereby the bed sections may be extended horizontally to form a bed or folded within the housing with one section extending substantially vertically, one section horizontal and one section inclined upwardly and rearwardly; an invertible seat pivotally connected to the housing for the support of said foldable bed frame both in the folded and unfolded position; pivotal connections between the seat and bed frame at the junction of the outer section and mid section, to lift the bed frame when the seat is lifted so as to move the bed frame outwardly around the rear end of the inner longer sections as a fulcrum; and to support the bed frame when the seat is inverted; floor supports for the seat when it is inverted; means connected with the said rear end of the inner bed section to cause the inner section to travel from a substan-

tially vertical position to a substantially horizontal position as the bed frame is opened.

7. A sofa bed comprising a sofa frame; a seat provided thereon to overturn; a folding bed frame consisting of two longer sections pivotally connected to a shorter mid section to form a bed or like folded in the sofa frame with one long section extending vertically, the mid section extending horizontally and the outer end section inclined upwardly and backwardly; means to guide one end section in the sofa frame; links connecting the bed frame and seat arranged to support said frame, both when the seat is used and when the seat is overturned, and means on the bottom of the seat for engaging the mid sections when the seat is overturned so as to prevent the rearwardly swinging of the seat around its hinges by the weight of the folded bed frame.

8. A sofa bed comprising a housing; a folding bed frame having two end sections pivotally connected to a mid section; connections to allow the bed to be folded up or extended; a seat hinged on the housing to overturn; the rear end of the rear end section of the bed being slidably pivoted in said housing; means to connect the frame and the seat in such a manner that the lifting of the seat from folded position swings the entire folded bed frame outwardly around the said rear ends as fulcrums; said rear end sections being moved from a vertical into a horizontal position by the unfolding of the bed sections; and means extending from the bottom of the seat for engaging the mid section when the seat is overturned so as to prevent the rearward swinging of the seat around its hinges by the weight of the folded bed frame.

In testimony whereof, I have hereunto set my hand at San Francisco, California, this 28th day of April, 1928.

JOSEPH D. BELL.
